JOSEPH R. FINNEY, OF YOUNGSTOWN, OHIO.

Letters Patent No. 87,921, dated March 16, 1869.

IMPROVED WHIP-SOCKET AND REIN-HOLDER COMBINED.

The Schedule referred to in these Letters Patent and making part of the same.

To all whom it may concern:

Be it known that I, JOSEPH R. FINNEY, of Youngstown, in the county of Mahoning, and State of Ohio, have invented a new and improved Combined Whip-Socket and Line-Holder; and I do hereby declare that the following is a full, clear, and exact description of the construction and operation of the same, reference being had to the accompanying drawings, making a part of this specification, in which—

Figure 1 is a perspective view.

Figure 2 is a horizontal section through line $x-x$ of fig. 1.

The object of this invention is to provide a neat, cheap, and convenient device, which shall serve both as a whip-holder and rein-holder, being attached, for that purpose, to any convenient part of the carriage. To this end,

The invention consists in a metallic base-plate, which can be attached, in any suitable manner, to the carriage, supporting, at one end, two standards, to one of which the whip-socket is attached, by a spring-hinge, in such a manner that the spring presses the socket against the opposite standard, and clamps the reins between it and that standard.

In the drawings—

A is the base-plate.

B is one of the standards, bent slightly, as seen at b.

C is the other standard, nearly parallel to the first, and about an inch from it.

D is the whip-socket, attached, by a hinge, d, to the

standard C, and by a spring, e, pressed against the standard B.

The socket may be provided with a slight knob, m, which shall not allow it to come quite in contact with the standard, so that the reins can be conveniently placed between them.

The upper end of standard B, bent outward from the socket, as shown in fig. 1, serves as a guide to receive the reins readily.

The whole apparatus may be covered with leather, and may be made of metal, hard rubber, or any other suitable material.

The operation of the device is clearly shown in fig. 2, the red lines indicating the position of the socket when the reins are not held by it, and the buff lines indicating its position and action in holding the reins.

Having thus described my invention,

What I claim as new, and desire to secure by Letters Patent, is—

1. The combined whip-socket and rein-holder, composed of the parts A, B, C, and D, spring s, and hinge d, substantially as and for the purpose specified.

2. The combination of a tubular whip-holder with a rein-holder, the whole being constructed in one instrument.

To the above specification of my invention, I have signed my hand, this 10th day of October, 1868.
